UNITED STATES PATENT OFFICE

LEO SIMMONS, OF WASHINGTON, DISTRICT OF COLUMBIA

CEILING ELECTRIC-LIGHT FIXTURE

Application filed September 23, 1926. Serial No. 137,288.

This invention provides a ventilated ceiling electric light fixture constructed and arranged to carry electric lights and permit electric wiring for such lights that will be in accordance with municipal and governmental electric wiring regulations and requirements, and the objects and nature of the invention will be readily understood by those skilled in the art in the light of the following explanations of the accompanying drawings that illustrate what I now believe to be the preferred mechanical expression or embodiment of the invention from among other forms, constructions and arrangements within the spirit and scope thereof.

An object of the invention is to provide a ventilated electric light fixture for location at the ceiling with the ends in view of providing a convenient support for electric lights and enclosed protecting passages for the electric wiring leading to such lights and for the application of the terminal or distributing boxes for such electric wiring, as well as for the arrangement of the electric lights to freely permit adjustment to control and promote the up or off flow of air heated by such lights, and incidentally the ventilation of the room.

With these and other objects in view, the invention consists in certain novel features in construction or arrangements, and in combinations as more fully and particularly set forth and specified hereinafter.

Referring to the accompanying drawings forming a part hereof:

Fig. 1 is a perspective view showing an embodiment of my invention applied to a ceiling, the ventilator or closure disk being shown approximately in closed position.

Fig. 2 is a detailed sectional elevation.

Fig. 3 is a detailed plan of the fixture, a portion of the annulus being shown in horizontal sections, dotted lines indicating wiring, the terminal or distributing box being indicated by dotted lines.

Fig. 4 is a vertical section, the electric light pendants not being shown, dotted lines indicating certain wiring.

Fig. 5 is a detailed cross section through the terminal box.

In the drawings, the ceiling 1, of a room or other enclosure is shown. To provide for ventilation, and for the application of the electric light fixture of my invention to this ceiling, a suitable opening *a*, usually circular, is formed vertically through the ceiling so as to open into an air space above the ceiling, or into an offtake air duct between joists 2.

The electric light fixture of my invention embodies a metal ring or annulus 3 that is set into the opening 2 from the lower end thereof and this annulus is suitably secured, as by screws 4, usually approximately flush with the ceiling and provides a vertical air escape opening in continuation of the opening *a*.

The annulus also carries the ventilator or closure disk 6, for opening and closing the lower end of the ventilating flue or opening *a*.

The annulus 3 provides a central, preferably elevated, support for the disk 6. For instance in the particular example illustrated, I show the annulus formed with several spaced rigid arms 7, in this instance arranged radially of the annulus and converging inwardly and at their inner ends joined to or integral with a central elevated hub 8 having a vertical internally threaded bore.

This hub 8 carries the closure disk 6 through the medium of a vertical central screw or longitudinally threaded spindle 9, at its lower end secured to the center of the disk 6 and upstanding therefrom through the hub 8, and in mesh with the thread thereof. The upper end 9^a of this screw 9 is preferably enlarged to limit the downward movement of the screw. The lower end of the screw preferably extends through a central opening in the closure disk, and the disk is clamped and normally fixed to the screw by means of upper clamp nut 10 and lower ornamental nut 11, bearing against the upper and under portions of the disk respectively. By this arrangement the electric light fixture parts can be readily assembled after the annulus 3, has been fixed in the ceiling. The lower end of the screw 9 can be inserted in the hub 8, and screwed downwardly therethrough, before the disk 6 is applied to the screw. Thereafter, the nut 10 can be screwed a short dis-

85
90
95
100

tance onto the screw 9 from the lower end thereof, the disk 6 can be slipped onto the lower end of the screw 9 and against the nut 10, and the ornamental nut 11 can then be 5 screwed onto the projecting reduced lower end of the screw 9 to tightly and rigidly clamp the central portion of the disk between nuts 11 and 10. Certain advantages in manufacture and assembly are gained by this 10 arrangement.

The underside of the horizontally disposed disk 6 is ornamental in character and is preferably so formed as to provide shoulders or 15 projections to engage the end of a cane or other article by which the disk can be rapidly rotated in either direction from within the room to raise or lower the disk to close or open the ventilating opening.

It will be noted that the disk 6 is located 20 and accessible from within the room to be ventilated and that the disk is located below the ventilating opening and below the annulus and that it closes up against the annulus and drops below the annulus when manipulated to open the ventilating duct *a*, for outward passage of air.

It is exceedingly desirable to provide these 25 vertical ceiling ventilating openings, in the central portion of a ceiling, the portion of the ceiling that is usually occupied by electric light fixtures, or from which electric light fixtures usually hang. It is also exceedingly 30 desirable to provide for the cooling of ceiling electric lights, by the removal of the highly heated air from such light.

For this purpose, among others, I utilize, 35 the ventilator annulus, as a support to carry two or more symmetrically arranged electric lights, so that the electric bulbs carried by 40 such lights will be below and more or less adjacent to the ventilating flue *a*, and in the path of the direct upflow of air to and through the flue *a*.

In the particular example illustrated, the 45 supporting annulus, considered as an entirety, is hollow or tubular, and is composed of two annular sections, namely, the main or upper section 3, preferable, cast or otherwise formed in one piece with the arms 7 and the hub 8, said section 3, being trough-like or inverted U-shape in cross section, and the bottom section 3^a, in the form of a flat metal ring fitted to the under side of the trough section 3, to close the same. The two sections 50 3, 3^a, are secured together by any suitable means, for instance by vertical machine screws 3^c.

The approximately flat ring 3^a, is preferably of enlarged external diameter with 55 respect to the corresponding diameter of trough-section 3, of the annulus, to close up against the bottom edges of the trough section 3, and form an outwardly projecting annular flange lapping the under surface of 60 the ceiling and covering the joint and ceiling

raw edge around trough 3. This ring 3^a, also forms the stop limiting the upward closing rotation of closure disk 6.

The electric light bulb sockets 12, that receive the light bulbs 13, are carried by and 65 hung from the annulus section or bottom ring 3^a, as by chain link or other suitable hangers 14, embodying eye bolts or screws 15, depending from and clamped to or screwed into the ring 3^a. The ring 3^a, is shown formed with 70 vertical holes 3^b, to receive the longitudinally hollow or tubular nipples or shanks 15^a, of eye bolts 15, secured therein by screw threads or other suitable means.

The annulus section 3, is also constructed 75 and arranged to receive and carry the terminal or distributing box 17, for the electric wiring. This terminal box can be of the usual construction with an inlet opening 17^a, for 80 the cable or metal tube 18 enclosing the wires 85 from the house wiring which cable extends into the box and is secured therein by the common clamp 18^a. This box also has a bottom outlet for the various wires 16 leading from the cable to supply the various light 90 bulb sockets 12. This outlet is through a tubular threaded nipple 17^b, at its upper end opening into the box 17, and at its lower end depending from the box and screwed into a 95 tapped or threaded hole 3^c, in the annulus 3. In the example shown, the hole 3^c, is vertical and extends through the top wall of the annulus, and the nipple 17^b, when screwed thereinto, supports the box in a vertical position 100 upstanding from the annulus. The lower end of the nipple opens into the hollow annulus. The separated wires 16 of the cable 105 pass from the nipple into the interior of the annulus and extend within the annulus to their respective openings 3^b and the hollow shanks 15^a, therein, through which they are threaded to descend to their respective bulb 110 sockets 12, all in accordance with municipal and governmental electric wiring requirements.

The bottom wall 3^a, of the hollow ventilator annulus can be formed throughout the circle thereof with a multiplicity of vertical holes 3^b, to accommodate any desired number of 115 electric light pendants equal to or less than the full number of holes 3^b, according to the requirements of each installation.

It will hence be noted that two or more 120 electric light bulbs can be carried by and arranged below the supporting annulus, and that said annulus carries, encloses and protects the electric wiring leading to the lights depending from the annulus, and that the annulus also carries the terminal box for the 125 wiring, and that said box is concealed from below when the annulus is fixed in the ceiling. In fact, the electric lighting fixture, the wiring therefor, and the ceiling ventilator, are carried by the annulus.

The ventilator disk 6, is freely accessible 130

from below for rotation and consequent up and down movement within the room and below the ceiling, without interference from the electric lights as the diameter of the annulus exceeds the diameter of the ventilator disk, and the lights depend from said annulus. This arrangement also promotes the up flow of heated air from the light bulbs, to the air outlet flue *a*, past the circumferential edge of the ventilator disk.

The electric light fixture construction is designed to permit easy wiring for the lights, of any particular installation, after the fixture has, in part at least, been secured in the ventilating flue in the ceiling. For instance, the trough like section of the annulus, with the terminal box mounted thereon, (without the bottom plate *3^a*, and the ventilator disk and its threaded spindle) can be properly located and to or in the ceiling in or surrounding the ventilating flue *a*. The opening through the annulus is then unobstructed, except for the arms *7*. The mechanic from either above or below, can insert the flexible metal tube *18* carrying the wires *16*, from the house wiring, into the terminal box *17*, and properly secure the same therein by the usually employed clamp *18^a*, with the wires *16*, extending down through the box and the tubular nipple *17^b*, to hang freely through the trough of the annulus. The bottom or cover plate *3^a* having the required number of eyes *15*, secured therein, can then be brought to position below the annulus, and the free end wires *16* can be threaded down through their appropriate tubular nipples *15^a*, of the eyes *15*. Said bottom plate is then fitted to the trough of the annulus and firmly secured thereto, the wires *16* being pulled down through the eye nipples, to assume their desired positions in and around the then completed and closed annulus.

The lower end of the spindle *9* (separated from the closure disk) can then be inserted in and screwed down through hub *8*, and thereafter the disk *6*, can be secured to the lower end of the spindle as hereinbefore described.

The bottom plate or ring *3^a*, is provided with a plurality of points *3^b*, for the attachment of electric light pendants, preferably uniformly spaced around the circle of the ring. For instance, in the particular example illustrated I happen to show twelve such points. The arrangement is such that the number of lights required by any particular installation from, say, two up to and including twelve, can be applied to provide a balanced or symmetrical arrangement. The plate is preferably constructed with the full number of attaching points clearly indicated thereon with the metal at said points weakened so that portions thereof can be easily broken or punched through to provide the number of holes *3^b*, spaced to meet the light requirements of the particular installation.

It is evident that various changes, modifications, and variations might be resorted to without departing from the spirit and scope of the invention, and hence I do not wish to limit the invention to substantially the exact disclosures hereof.

What I claim is:

1. A ventilated ceiling electric light fixture embodying an annulus adapted to be secured to a ceiling surrounding a vertical ventilating opening therethrough, said annulus provided with electric wire outlets and with an electric wire inlet, whereby the wires are enclosed within the annulus from the inlet to the outlets, said annulus in its bottom wall providing for the attachment of electric light supporting means.

2. A ventilated ceiling electric light fixtures embodying a supporting annulus of trough formation to receive electric light wires, a terminal box rising from said annulus and opening thereinto, and a bottom plate for closing the trough of said annulus and having wire outlets therefrom and depending electric light supports.

3. An electric light fixture embodying an annulus in the form of an inverted annular trough, and an annular bottom plate removably secured to the trough and covering the open bottom thereof, said annulus adapted to support electric light supports and having an inlet for wires leading to and distributed within the annulus and wire outlets leading to said electric lights.

4. A ventilated ceiling electric light fixture embodying a supporting annulus for depending electric lights and adapted to be secured surrounding a vertical ventilating opening in a ceiling, said annulus provided with a central fixed vertical nut in said opening and nut supporting arms connecting the annulus and nut; a closure disk for said opening and arranged below said annulus; a longitudinally threaded central spindle upstanding from and supporting said disk and meshing with and freely rotatable in said nut and at its upper end above the nut formed with a stop to prevent downward detachment from the nut; said disk having a central vertical hole removably receiving the lower end of the spindle; and means for normally rigidly clamping the disk on the lower end of the spindle.

5. A ventilating ceiling electric light fixture provided with means for supporting electric lights below a vertical ventilating outlet through the ceiling, said fixture embodying a supporting annulus to be secured to the ceiling surrounding said outlet and provided with a central member and arms supporting the same from the annulus in said outlet; and a closure disk for and arranged below said outlet and the annulus, and supported from said central member and movable vertically with respect thereto to cooperate with

the annulus to control said outlet, said disk being accessible for raising and lowering from within the room, said disk being arranged with respect to said electric lights to move vertically toward and from said annulus without interference with said electric lights and the supporting means therefor.

5 Signed at Washington, D. C., this 21st day of September, 1926.
